UNITED STATES PATENT OFFICE.

JOHN F. HUCKEL, OF KANSAS CITY, MISSOURI.

DESIGN FOR A VENDING-TRUCK FRAME.

48,352.

Specification for Design.

Patented Dec. 28, 1915.

Application filed September 23, 1915. Serial No. 52,322. Term of patent 14 years.

To all whom it may concern:

Be it known that I, JOHN F. HUCKEL, a citizen of the United States, residing at Kansas City, in the county of Jackson and State of Missouri, have invented a new, original, and ornamental Design for a Vending-Truck Frame, of which the following is a specification, reference being had to the accompanying drawing, forming a part thereof.

The figure is a perspective view of a vending truck frame, showing my new design.

I claim:

The ornamental design for a vending truck frame, as shown.

JOHN F. HUCKEL.

Witnesses:

LYNN A. ROBINSON,
LETA E. COATES.
